UNITED STATES PATENT OFFICE.

RUSSELL WILES, OF RIVERSIDE, ILLINOIS, ASSIGNOR TO STANDARD OIL COMPANY, OF WHITING, INDIANA, A CORPORATION OF INDIANA.

ART OF REFINING OILS.

Application filed July 11, 1921. Serial No. 483,861.

To all whom it may concern:

Be it known that I, RUSSELL WILES, a citizen of the United States, residing at Riverside, in the county of Cook and State of Illinois, have invented a new and useful Improvement in the Art of Refining Oils, of which the following is a specification.

The present invention relates to improvements in the refining of hydrocarbon oils, and more particularly to the recovery of volatile hydrocarbons, such as lighter gasoline fractions, from refining and natural gases.

In accordance with the present invention the hydrocarbon gases to be treated for the recovery of gasoline constituents are subjected to the absorbent action of reduced crude oil, by which term is designated the residue resulting after distillation from crude oil of its kerosene and lighter constituents by steam or by steam and fire. A suitable reduced crude is, for example, a bottom obtained by distilling off 15 to 25% from a mid-continent crude with fire and steam. This may suitably be effected in a counter-current absorber of customary type, the absorber being held under the same pressure as the gases being treated or higher. The gas freed from its gasoline constituents passes into a dry gas line which leads it to a suitable reservoir.

The reduced crude oil leaving the absorbers carries with it the absorbed gasoline constituents of the gas. These, in general, are not properly proportioned for a motor fuel gasoline, the proportion of higher boiling point fractions of high fuel value being low. This reduced crude oil is next admixed with normal crude oil containing its natural kerosene and lighter fractions. The proportion of the reduced crude absorber liquid may suitably be 20 to 50% of the mixture. The mixed oils are subjected to fractional distillation. This fractional distillation may be a dry distillation, for example, in the crude or coking stills, or it may be effected with the aid of an inert gas, such as steam. In the fractionation of the mixture the gasoline constituents absorbed in the reduced crude are driven off at the same time as the natural gasoline constituents of the crude oil, and are blended with the excess of less volatile gasoline constituents of the normal crude oil to form a properly balanced motor fuel product. The gasoline constituents of

the crude oil thus utilized are those which ordinarily find their way into the intermediate product generally known as naphtha bottoms. The gas passed thru the absorber may suitably be, when convenient, the uncondensed gas from the stills in which the above described distillation is carried out.

The accompanying drawing illustrates in chart form the flow of the process.

Although the present invention has been described in connection with the details of a specific embodiment thereof, it is not intended that these details shall be regarded as limitations upon the scope of the invention, except in so far as included in the accompanying claims.

I claim:

1. The process of refining oils for the production of gasoline which comprises subjecting hydrocarbon gases containing gasoline constituents to the absorbent action of reduced crude oil, admixing the reduced crude oil with crude oil containing gasoline and heavier constituents and fractionally distilling the mixture.

2. The process of refining oils for the production of gasoline which comprises subjecting hydrocarbon gases containing gasoline constituents to the absorbent action of reduced crude oil, admixing the reduced crude oil with crude oil containing gasoline and heavier constituents and distilling the mixture by the conjoint application of heat and an inert gas.

3. The process of refining oils for the production of gasoline which comprises subjecting hydrocarbon gases containing gasoline constituents to the absorbent action of reduced crude oil, admixing the reduced crude oil with crude oil containing gasoline and heavier constituents and fractionally distilling the mixture, and subjecting the gases evolved and uncondensed during such distillation to the absorption step of the cycle.

4. The process of refining oils for the production of gasoline which comprises subjecting hydrocarbon gases containing gasoline constituents to the absorbent action of reduced crude oil, admixing the reduced crude oil with crude oil containing gasoline and heavier constituents, the said reduced crude forming 20 to 50% of the mixture, and fractionally distilling the mixture.

RUSSELL WILES.
